UNITED STATES PATENT OFFICE.

WALTER D. HARPER, OF FLORENCE, SOUTH CAROLINA.

FIREPLACE HEATER.

Application filed February 6, 1922. Serial No. 534,501.

To all whom it may concern:

Be it known that I, WALTER D. HARPER, a citizen of the United States, residing at Florence, in the county of Florence and 5 State of South Carolina, have invented certain new and useful Improvements in Fireplace Heaters, of which the following is a specification.

This invention relates to a sectional fireplace heater or boiler which may be placed in the ordinary fireplace of a dwelling to conserve the heat from the gases of combustion which are ordinarily wasted by the passage of the gases directly into the chimney. 10 With a heater constructed in accordance with my invention, the greater part of this heat is absorbed by the water in the heater which may then be circulated through radiators to heat other parts of the dwelling. 15 The heater is composed of hollow metal sections which may be readily assembled in the desired number to fill the fireplace, and these sections are so designed as to form a tortuous flue through which the gases must 20 flow in passing to the chimney. The heater is also provided with a front frame and doors by which it may be entirely enclosed in the fireplace, or these doors may be swung open to permit the direct radiation of heat 25 into the room. In addition to the damper for admitting air under the grate of the heater, I provide means whereby air, in regulated volume, may be fed into the space 30 above the grate to promote combustion of the gases.

In the accompanying drawing,

Fig. 1 is a front elevation of the heater arranged within a fireplace;

Fig. 2 is a central vertical section through 40 the same;

Fig. 3 is a section on the line 3-3 of Fig. 2;

Fig. 4 is a section on the line 4-4 of Fig. 2; and,

Fig. 5 is a perspective view on a small scale of one of the flue sections of the heater.

Referring to the drawing, *a* represents a chimney having a fireplace *b*, in which is arranged a heater of my invention. The heater is enclosed within the fireplace by a metal frame or casing *c*, having a pair of outwardly swinging doors *1*, and having a grating *2* beneath the doors in which is arranged a sliding damper *3*. The heater proper comprises two flat hollow side sec-

tions *d-d'*, between which are arranged a plurality of intermediate hollow sections *e*, *e'*, etc., which may, for convenience, be termed flue sections. The flue sections are similar in general form, but vary in width 60 and number, to suit the width of the fireplace. One of the flue sections, preferably the central one *e²*, is provided at the top with a threaded outlet nipple *4*, and at the bottom with a threaded inlet nipple *5*, whereby a radiator system may be connected to the water sections of the heater. This section is also provided with a clean-out passageway *6*, leading from the smoke passage-way of the section. 65

The side sections, which are in the form of hollow slabs, extend from the front casing *c* to the back wall of the fireplace and from the base *a'* to approximately the top of the fireplace. The flue sections, which are connected to one another and to the side sections as hereinafter described, have the same height and the same depth across the top, from front to rear, as the side sections, the major portion of each flue section having 70 less depth and being at the rear of the grate *g*. As shown in Figs. 3 and 5, each flue section comprises a front water-leg *7*, of less height than the heater, which, when the heater is assembled, extends upwardly at the 75 rear of the grate *g* and the combustion space *h*, a rear water leg *8*, spaced from the front leg and extending upwardly for the full height of the heater, a top portion or compartment *9* which extends forwardly from 80 the rear leg to the casing *c*, and an intermediate water leg *10*, which extends downwardly from the top compartment between the front and rear water legs. It will be seen that in the assembled heater the upper 85 compartments form a top for the heater and the water legs form a flue *12*, which extends from the combustion space over the legs *7*, thence downwardly between the legs *7* and 90 *10*, and thence upwardly between the legs *8* and *10*. The walls of the top compartments are narrowed, as shown at *9^a*, between 95 the front and intermediate water legs, in order to provide vertical channels *12^a*, between the adjacent sections for the escape of the products of combustion into the chimney, these channels forming continuations of the flue. With this construction, it 100 will be evident that the hot gases will flow in contact with both walls of the front and 110

intermediate legs and in contact with the inner wall of the rear legs and the top compartment, and most of the heat in the gases will be taken up by the water in the heater before the gases pass into the chimney.

The sections of the heater are connected together by several series of alined nipples. Thus, in the lower parts of the walls of the several sections are alined threaded openings 13, and fitting in the openings in the adjacent walls of the sections are threaded nipples 14. The openings 13 in the outer walls of the side sections are closed by removable threaded plugs 15. These nipples form communicating passageways between the water spaces in the base portions of the several sections. Similarly, the water spaces of the legs 10 are connected together at their lower ends and to the side sections by nipples 16, 20 the openings in the outer walls of the side sections in line with these latter nipples being closed by plugs 17. The upper ends of the water legs 7 are connected together and to the side sections by nipples 18, and the 25 upper ends of the water legs 8 are connected together and to the side sections by nipples 19, the openings in the outer walls of the side sections, opposite the nipples 18, being closed by plugs (not shown), and the 30 openings in the walls of the side sections, opposite the nipples 19, being closed by plugs, shown at 20. These several sets of nipples hold the 35 several sections together and it will be evident that the heater sections may be assembled by securing them successively together by means of the nipples and then inserting the plugs in the side sections; also that the sections may be readily taken apart by removing the plugs from one or both of the 40 side sections and unscrewing the nipples between the several sections successively by means of a suitable wrench.

In addition to the damper 3, for admitting air beneath the grate, I provide means for admitting air to the space *h* above the grate. As shown, each of the side sections of the heater is cast with an air conduit 21, having a part adapted to extend through the casing *c*, as shown in Fig. 3. This conduit extends 45 through the side section and rearwardly along its inner wall to the adjacent flue section. Each flue section has on the forward wall of the leg 7, a transverse conduit section 21^a and when the heater is assembled these 50 conduit sections meet end to end and connect with the conduits 21 on the side sections, thus forming a continuous conduit. This conduit is provided with a plurality of spaced perforations 21^b on its underside, 55 through which air may pass into the combustion space *h*. Dampers 22 are provided at the inlet ends of the conduit for regulating the inflow of air. It will be evident that when a fire is burning in the grate, the draft 60 through the heater will cause air to flow

through the conduit 21 into the heater and this air will cause more complete combustion of the gases.

The grate may be of any desired form. As shown, the grate *g*, which is of basket form, is supported by lugs 23 on the front frame and a cross bar 24 which extends between the side sections. The top of the heater, at its forward edge, projects over a horizontal supporting ledge 25 which is cast integral with the front frame. The cleanout flue 6 is normally closed by a door 6^a which is swung from brackets 6^b immediately above the flue.

From the foregoing description the operation will be clear. When the heater is not in use, the doors 1 will be left closed. When the heater is in use, the doors may be left open to permit the heat to be radiated directly into the room, or may be closed or partly closed to regulate the temperature in the room. Air may be admitted through the lower damper and also as desired through the conduit 21 to promote combustion. As the heat must travel through the extended flue space in the heater, a great deal of the heat will be absorbed by the water, and since the sections are so connected that the water may circulate through the sections and rise as it becomes heated to the outlet 95 nipple 4, the heater may be used to heat radiators at distant points by connecting the radiator pipes to the inlet and outlet nipples of the radiator. It will be noted that the water as it becomes heated can rise in the rear legs of each section to the top of the heater; also it may rise in the front leg to the nipples 18 and then flow into the side sections and from the upper parts of the latter, through the nipples 19 to the 100 outlet 4, and similarly, the water which becomes heated in the intermediate legs 10 will rise and flow to the side outlet, cooler water passing from the side sections through the nipple 16 to replace the water flowing upward in the legs 10.

What I claim is:

1. A fireplace heater comprising hollow side sections and intermediate hollow flue sections having communicating passageways, each flue section having a base portion, front and rear water-legs extending upwardly from the base portion, a top portion extending forwardly from the rear leg over said front leg, and an intermediate water-leg depending from said top portion between said front and rear legs.

2. A fireplace heater comprising hollow side sections and intermediate hollow flue sections, each flue section having a base portion, front and rear water-legs extending upwardly from the base portion, a top portion extending forwardly from the rear leg over said front leg, an intermediate water-leg depending from said top portion between

said front and rear legs, and nipples connecting, respectively, the base portions and the corresponding leg portions of the flue sections together and to the side sections.

5. A fireplace heater comprising hollow side sections and intermediate hollow flue sections, each flue section having a base portion, front and rear water-legs extending upwardly from the base portion, a top portion 10 extending forwardly from the rear leg over said front leg, an intermediate water-leg depending from said top portion between said front and rear legs, and nipples connecting, respectively, the base portions, the 15 upper ends of the front and rear legs and the lower ends of the intermediate legs together and to the side sections.

4. A fireplace heater comprising hollow side sections and intermediate hollow flue 20 sections having communicating passageways, each flue section having a base portion, front and rear water-legs extending upwardly from the base portion, a top portion extending forwardly from the rear leg 25 over said front leg and an intermediate water-leg depending from said top portion between said front and rear legs and forming therewith a downwardly and thence upwardly extending flue, said top portions being restricted in width between the rear and intermediate legs to provide outlets for said flue, and one of said sections having a water inlet in its base portion and a water outlet 30 in its top portion.

5. A fireplace heater comprising hollow side sections and intermediate hollow flue 35 sections having communicating passageways, each flue section having a base portion, front and rear water-legs extending upwardly from the base portion, a top portion extending forwardly from the rear leg over 40 said front leg and an intermediate water-leg depending from said top portion be-

tween said front and rear legs and forming therewith a downwardly and thence upwardly extending flue, said top portions being restricted in width between the rear and 45 intermediate legs to provide outlets for said flue, and one of said sections having a clean-out passageway extending from the lower part of the flue to the front of the section.

6. A fireplace heater comprising hollow side sections and intermediate hollow flue 50 sections having communicating passageways, each flue section having a base portion, front and rear water-legs extending upwardly from the base portion, a top portion 55 extending forwardly from the rear leg over said front leg and an intermediate water-leg depending from said top portion between said front and rear legs and forming therewith a downwardly and thence upwardly extending flue, said top portions being restricted in width between the rear and intermediate legs to provide outlets for said flue, and one of said sections having a water inlet in its base portion and a water outlet 60 in its top portion.

7. A fireplace heater comprising hollow side-sections and intermediate hollow flue sections having communicating passageways, said flue sections having front, rear 70 and intermediate water-legs arranged to form a tortuous flue, each side section having a perforated air conduit on its inner wall and extending to the front of the heater, and said flue sections having perforated conduit sections on their front legs 75 adapted to form continuations of said air conduit in the assembled heater, and a grate below said air conduit.

In testimony whereof I affix my signature. 80

WALTER D. HARPER.
